AIR CONDITIONING APPARATUS

Robert R. Candor, Dayton, Ohio, assignor to General Motors Corporation, Dayton, Ohio, a corporation of Delaware

Application November 8, 1935, Serial No. 48,893

6 Claims. (Cl. 62—6)

This invention relates to refrigeration and more particularly to the conditioning of air.

An object of this invention is to provide an improved arrangement and control of the refrigeration for the conditioning of air.

Further objects and advantages of the present invention will be apparent from the following description, reference being had to the accompanying drawings, wherein a preferred form of the present invention is clearly shown.

In the drawings:

Fig. 1 is a diagrammatic representation of an apparatus embodying features of my invention;

Fig. 2 is a wiring diagram for the apparatus shown in Fig. 1;

Fig. 3 is a diagrammatic representation of another embodiment of my invention;

Fig. 4 is a wiring diagram for the apparatus shown in Fig. 3; and

Fig. 5 is a diagrammatic representation of another embodiment of the invention.

In accordance with this invention, air is contacted with a relatively warm evaporator and with a relatively cold evaporator. The refrigerant from the cold evaporator is introduced into a first compressing unit. The refrigerant from the warm evaporator and from the first compressing unit is introduced into a second compressing unit from whence the vapors are condensed in a unitary condenser which is connected to the evaporator. Also the air may be cooled by a water-flow means or coil which is placed in parallel relationship with the evaporating means, and the water flowing through this device is used to cool the condenser. Also, when desired, the operation of the refrigerating apparatus is modified or stopped when a certain quantity of water has been removed from the air which is being conditioned in order to prevent the overflow of water.

In the modification shown in Fig. 1, air is caused to flow through a passageway 10 by means of a fan 11 driven by the motor 12. The air flows past a relatively warm evaporator 13 and a relatively cold evaporator 14. It also flows, in parallel relationship, past a water-flow means or coil 15. If desired, a damper 16 may be provided so that air need be circulated past the water coil only during mild weather. Under such conditions, if desired, the motor 12 may be made to have a plurality of speeds and the speed of the fan may be regulated in accordance with the position of the damper 16. Thus, if desired, the speed of the fan 11 may be slower when air is forced only over the water coil 15 than when it is forced over all of the coils. The speed of the fan

may also be varied even when the air flows over all of the coils. The evaporating means 13, 14 may be connected to compressing means 17 which in turn is connected to condensing means 18. The water flowing through the coil 15 from the pipe 19 may flow through the pipe 20 and through the condenser to cool the same, and may be discharged at 21. Means for causing the automatic flow of water in accordance with the compressing action may be provided, and this may take the form of a pressure responsive valve 22 which opens with the increasing head pressure such as in the condenser 18 acting through the tube 23a. When the cooling coil 15 is to be used alone, the hand valve 22a may be opened, so that water may flow through the coil 15 independently of the automatic valve 22.

If desired, the compressing means 17 may take the form of a first sealed motor-compressor unit 23 which is connected by the suction line 24 with the relatively cold evaporator 14. A second sealed motor-compressor unit 25 is connected by the suction line 26 with the relatively warm evaporator 13 and also to the discharge of the unit 23 by means of the pipe 27. The units 23 and 25 thus discharge into the condenser 18 through the pipe 28. Liquid refrigerant from the condenser 18 flows through the pipe 29 to the evaporators 13 and 14. Refrigerant is introduced into the evaporator 14 by means of an automatic expansion valve 30 which is automatically throttled by the bulb 31 placed at the outlet of the evaporator. The valve 30 is of the type which automatically introduces liquid refrigerant into the evaporator 14 when the pressure therein is reduced below a predetermined limit, except that when it is throttled by the bulb 31 the flow of refrigerant is reduced or stopped regardless of suction pressure. Refrigerant is introduced into the evaporator 13 through the valve 31 which is throttled by the bulb 32. The valve 31 is similar in action and function to the valve 30 except that it is calibrated at a higher pressure or temperature than the valve 30. Both valves 30 and 31 may be calibrated to open at temperatures such that freezing of water is avoided, although it is to be understood that, if desired, the setting may be selected to freeze moisture.

The apparatus disclosed in Fig. 1 may be automatically controlled in accordance with air conditions. Also, if desired, the motor-compressor units 23 and 25 may be caused to start in sequence in order to reduce the starting load on the electric line. A wiring diagram for accomplishing this is shown in Fig. 2, in which 30 and

31 are the electric power lines. The operation of the apparatus may be manually controlled by a manual master switch 32. The closing of this switch places the apparatus under the control of an air condition responsive switch and causes the motor 12 to operate at a selected speed. A speed selector 33 may be provided to govern the flow of current through the motor 12 and regulate its speed. An instrument or switch 34, responsive to air conditions, governs the operation of the motor-compressor units by starting and stopping them. The instrument 34 may be a switch which is responsive either to dry bulb air conditions, wet bulb air conditions or a combination of both, such as effective air temperature conditions or relative humidity conditions. The closing of the switch 34 causes current to flow through the main winding 35 of the motor 25a of either the unit 25 or 23. The current flows from the line 30, switch 34, winding 35, solenoid 36 and bi-metal 37 to the line 31. The flow of current through the solenoid 36 closes the contacts 38 thus causing current to flow through the starting winding 39. After a sufficiently long period of time to permit the motor to attain its speed, the bi-metal 37 becomes sufficiently heated to close the contacts 40 thus shunt the solenoid 36. This in turn opens the contacts 38, and the motor continues to operate on its running winding only. An overload switch 41 is provided with a bi-metal 42. This bi-metal may be heated by the heater 43 which becomes sufficiently heated to open the switch 41 only when the motor 25a is overloaded.

The motor 23a, of either the unit 23 or 25, may be started in sequence to the motor 25a by any suitable means. This may be accomplished by placing a delay switch 44 across the motor 23a and under the control of the switch 34. When the switch 34 closes and starts the motor 25a it also simultaneously causes the flow of current through the delay element or heater 45 of the switch 44. After the bi-metal 46 has become sufficiently heated, it closes the contacts 44. The heating period of the bi-metal 46 is so calibrated that it does not close at 44 until after the motor 25a has attained its full speed and after the contacts 40 have closed. The closing of the contact 44 starts the motor 23a in a manner similar to that of motor 25a. Thus the motor 23a is provided with a main winding 47, a running winding 48, a solenoid 49, a starting switch 50, a bi-metal switch 51 and an overload switch 52 operating in substantially the same manner as the corresponding elements of the circuit of motor 25a. The bi-metals of the overloads 52 and 42 automatically reset themselves after a relatively long period of time and continue to try to start their respective motors with a sufficient time interval of idleness to prevent overheating of the motors.

In the modification shown in Fig. 3, a cabinet or casing 50 is provided and may be placed in a room or the like. Air to be conditioned for the room may enter at the casing at 51, this air being recirculated air. Air from outside the room enters at 51a from the tube 51b under the control of hand valve 51c. The air flows past a relatively warm evaporator 52, and a relatively cold evaporator 53 under the impulse of a fan 54 driven by a motor 55, and is discharged into the room through the grille 56. The evaporators are connected to compressing means generally designated as 57 which discharge into a condensing means 58 which condensing means is connected with the evaporators through the pipe 75

59. Refrigerant is provided for the evaporator 52 through the automatic expansion valve 60 having a throttling bulb 61. Refrigerant for the evaporator 53 is provided by the valve 62 having a throttling bulb 63. The valves 60 and 62 are similar in function and operation to the valves 30 and 31 respectively. The compressing means 57 may take the form of a first sealed motor-compressor unit 64 connected to the cold evaporator 53, and a second sealed motor-compressor unit 65 connected to the warm evaporator 52 and to the discharge of the unit 64. These units discharge through the pipe 66 into the condenser 58.

15 Air is caused to flow from and to the outside of the room in which the cabinet 60 is placed, through the insulated compartment 75, in order to cool the refrigerant circulating or liquefying means. Thus a panel 70 is provided in the window 71. An air intake pipe 72 is connected with the machinery compartment and with the outside of the room through the panel 70. An air discharge pipe 73 is likewise connected with the outside of the room and with the machinery compartment. A blower 74 causes air to flow through the conduits 72 and 73 and through machinery compartment 75. A blower 74 is driven by a motor 76. An air relief opening 77 having a regulating valve 78 is provided for the withdrawal of air from the room by the blower 74 to compensate for the air entering at 51a. However, a window or door may provide such air relief instead.

35 The operation of the refrigerant liquefying means in the compartment 75 may be governed in accordance with air conditions and also may be modified or its operation may be prevented in accordance with the accumulation of water from the evaporators 52 and 53. If desired, the motor-compressor units 64 and 65 may be caused to start in sequence in a manner similar to the units 23 and 25 heretofore described. In addition, water condensed or frozen out of the air by the evaporators 52 and 53 may be gathered in a drain pan 80 which in turn may discharge into the receptacle 81 which operates a switch 82. The arrangement is such that when a certain quantity of water flows into the receptacle 81, the switch 82 is opened and further operation of the refrigerating apparatus is prevented until the receptacle 81 is emptied. This prevents the overflow of water.

55 The operation of the apparatus shown in Fig. 3 may be accomplished by the wiring shown in the diagram of Fig. 4. The electric power lines 83 and 84 supply electrical energy for the apparatus. A manual master switch 85 controls the entire apparatus. Its closing starts the operation of the motor 55, which also may be a variable speed motor. A switch 86 governs the operation of the liquefying unit in accordance with air conditions. The switch 86 may be the same in construction and function with the switch 34. When the switch 86 is closed, motor 76 starts and the motor 64a of the unit 65 is started in a manner similar to the motor 25a. Thereafter, or in sequence, the motor 64a of the unit 64 is started in a manner similar to the motor 23a. When the receptacle 81 becomes sufficiently full, it compresses the spring 87 and opens the switch 82. This prevents further operation of the compressors and motor 76 until the receptacle 81 is emptied.

70 Instead of discharging the condensed moisture into the receptacle 81 it may be discharged over

the condenser 58 where it is evaporated and its water vapor would be discharged through the pipe 73 outside of the room. This may be accomplished by providing a two-way valve 90 which may connect the drain pan 80 either with the pipe 91 or with the pipe 92 which latter pipe is connected with the distributor head 93 over the condenser 58.

In the modification shown in Fig. 5, a cabinet 100 may be provided and may be placed in a room. Air from the room or from outside the room or both may enter the cabinet at 101. It passes in thermal contact with the water-flow means or coil 102, a relatively warm evaporator 103, a relatively cold evaporator 104 and is discharged through the outlet 105 into the room. The flow of air may be caused by means of a fan 106 driven by a motor 107. The motor 107 may be a multiple speed motor similar to the motor 12. The evaporator 104 may be connected with a first sealed motor-compressor unit 108. The evaporator 103 may be connected with a second sealed motor-compressor unit 109. The discharge of the unit 108 may be into the unit 109, and these two units may discharge into the condenser 110. Water from the coil 102 may flow through the condenser coil 111. The flow of water may be governed in accordance with the head pressures by the valve 112 in a manner similar to that described for Fig. 1. A thermostatic switch 113 may govern the wiring arrangement for the units 108 and 109 in a similar manner to that described with respect to Fig. 2, the wiring arrangement being diagrammatically indicated by the square 114. In this manner the units 108 and 109 are caused to start in sequence in accordance with air conditions of the room.

In all of the modifications, it is understood that a thermostatic, humidostatic or other type of switch, such as 34, 86 or 113, may be made responsive to the conditions of the air of the room or space which receives the conditioned air or it may be responsive to the conditions of air outside such room or space or may be made responsive to a combination of the two.

While the form of embodiment of the invention as herein disclosed, constitutes a preferred form, it is to be understood that other forms might be adopted, all coming within the scope of the claims which follow.

What is claimed is as follows:

1. The method of conditioning air which comprises operating a fan to circulate air through a refrigerant evaporating zone and a water-flow zone in parallel, mixing the air passing from said zones, compressing refrigerant from said evaporating zone, condensing the compressed refrigerant with water from said water-flow zone, and varying the speed of said fan so as to vary the volume of air circulated.

2. An apparatus for conditioning air comprising fan means establishing a stream of air to be conditioned, a refrigerant-flow air cooler in said means, a water-flow air cooler in said means in parallel relationship to said refrigerant-flow air cooler, means for mixing the air from said refrigerant flow cooler with the air from said water-flow air cooler, a refrigerant liquefying unit connected to said refrigerant-flow air cooler, means for cooling said unit with water flowing

through said water-flow air cooler, means for bypassing at least a portion of the air around one of said air coolers, and means for varying the speed of said fan means.

5. A unitary room air conditioner adapted to be used near a window of said room and including a cabinet separate from the walls of said room, a cooling compartment and a machinery compartment in said cabinet, a plurality of evaporators in said air cooling compartment, means for maintaining one of said evaporators at a relatively high temperature, and means for maintaining one of said evaporators at a relatively low temperature, refrigerant liquefying means in said machinery compartment in refrigerant flow relationship with said evaporators, a first blower connected to said air cooling compartment, a second blower connected to said machinery compartment, said air cooling compartment being provided with an air inlet from said room, an air inlet from said window and an air outlet to said room, said machinery compartment being provided with an air inlet from said room, an air inlet from said window and an air outlet to said window, whereby fresh air from said window is cooled and is discharged into said room, and cooled air is circulated in said machinery compartment and out said window.

30. An air conditioning apparatus comprising an air cooling unit, a refrigerant circulating unit connected to said cooling unit, means responsive to changes in one function of the psychrometric condition of the air for governing the operation of one of said units, and means inherently responsive to the quantity of water vapor removed from air treated by said cooling unit for preventing operation of one of said units.

35. An air conditioning apparatus comprising a first evaporator having means for maintaining said evaporator at a relatively warm refrigerating temperature, a second evaporator having means for maintaining said evaporator at a relatively cold refrigerating temperature, said evaporators satisfying a common air cooling load, a first motor-compressor unit connected to said second evaporator, a second motor-compressor unit having its suction side connected to said first evaporator and to the discharge of said first unit, condensing means connected to said second unit and to said evaporators, and means inherently responsive to air conditions for starting said units in sequence.

40. An air conditioning apparatus comprising a first evaporator having means for maintaining said evaporator at a relatively warm refrigerating temperature, a second evaporator having means for maintaining said evaporator at a relatively cold refrigerating temperature, said evaporator satisfying a common air cooling load, a first sealed motor-compressor unit connected to said second evaporator, a second sealed motor-compressor unit connected to said first evaporator and to the discharge of said first sealed unit, condensing means connected to said second unit and to said evaporators, means for controlling the operation of said units in accordance with air conditions, and means for preventing the operation of said units in accordance with the dehumidification of air.

ROBERT R. CANDOR.
